CLAIM

The ornamental design for a cage for housing and confining pet animals, as shown and described.

DESCRIPTION

FIG. 1 is a front view of a cage for housing and confining pet animals, according to my new design;

FIG. 2 is a left side view thereof;

FIG. 3 is a right side view thereof;

FIG. 4 is a rear view thereof; and,

FIG. 5 is a top view thereof.

The front view of the cage depicts a flat, transparent panel, which forms a part of the front surface of the cage.

The bottom view of the cage is not visible in normal use and is not being claimed herein.
